Primary Examiner — Cynthia Ramirez*Assistant Examiner* — Llorellys Martinez-Rivera(74) *Attorney, Agent, or Firm* — JK Intellectual Property Law, PA(57) **CLAIM**

The ornamental design for a dual lit grab rail assembly, as shown and described.

DESCRIPTION

FIG. 1 is a perspective view of a dual lit grab rail assembly showing the present design;

FIG. 2 is a right side view thereof;

FIG. 3 is a left side view thereof;

FIG. 4 is a top view thereof;

FIG. 5 is a bottom view thereof;

FIG. 6 is a first end view thereof; and,

FIG. 7 is an opposite end view thereof.

The broken lines shown in FIGS. 1-7 illustrate portions of the dual lit grab rail assembly that form no part of the claimed design. The dual lit grab rail assembly is shown with a symbolic break in length. The appearance of any portion of the dual lit grab rail assembly between the break lines does not form part of the claimed design.
